UNITED STATES PATENT OFFICE.

GLEN B. HOAG, OF FULLERTON, CALIFORNIA.

CONCRETE-WALL FORM.

Application filed November 7, 1921. Serial No. 513,477.

To all whom it may concern:

Be it known that I, GLEN B. HOAG, a citizen of the United States, residing at Fullerton, in the county of Orange and State of California, have invented a new and useful Concrete-Wall Form, of which the following is a specification.

This invention relates to forms of the character employed in the construction of 10 poured concrete walls and an object of the invention is to facilitate the construction of such walls by providing a simple form which is easy to install in place and to remove from the section of wall constructed 15 by its use.

Another object is to provide a unit which can be employed for the construction of a solid wall or can be quickly combined or associated with another unit of the same 20 construction for use in making a hollow wall.

The accompanying drawings illustrate the invention:

Fig. 1 is a plan view of a series of form 25 units constructed in accordance with the provisions of this invention, and associated in such manner that the concrete for making a wall section may be poured into the form. Certain units are associated for the production 30 of a hollow wall, and one of the units is adapted for the construction of a connecting partition.

Fig. 2 is an enlarged elevation partly in section on line indicated by 2-2 Fig. 1. A 35 fragment of a section of hollow wall to which the form is clamped is also shown.

Fig. 3 is a perspective view of a single unit form.

Fig. 4 is a perspective view of a double 40 unit form constructed from two single units of the type shown in Fig. 3.

Referring first to Fig. 3 of the drawings there are provided spaced form plates 5, 6 which are provided, respectively, with upwardly extending members 7, 8 that constitute levers. The fulcrum or pivot of the lever 7 is shown at 9 and may be a bolt passing through a pair of straps 10. Also the lever 8 is fulcrumed or pivoted at 11 to the 45 straps 10. The fulcrums are just above the plates. The bolt 9 may be selectively placed in anyone of a series of holes 12 in the straps 10 so as to effect different spacings of the plates 5, 6 for the construction of different 50

thicknesses of walls. The members 7, 8 may 55 be secured to the plates 5, 6 by screws 13, or any other suitable fastening devices.

Near the upper end of the lever 7 is a screw-threaded hole 14 engaged by an adjusting screw 15 which has one end seated 60 in a socket 16 near the upper end of the lever 8 so that, for example, if the screw threads be right hand, turning of the screw 15 to the right will force the upper ends of the levers 7, 8 away from one another, and consequently move the lower edges of the plates 5, 6 toward one another in order that said plates may thus be securely clamped upon a section of foundation or previously constructed wall.

Means are provided to temporarily lengthen one side of the form and such means, in this instance, are constructed as follows: The plate 5 is provided with outwardly projecting studs 17 adapted to be detachably engaged by arms 18 secured by screws 19, or other suitable fastening devices, to a gate or plate-extension 20 which abuts one end of the plate 5 so as to lengthen one side of the form. The arms 18 are releasably 70 held on the studs 17 by wing nuts 21. It is clearly evident that when it is not desired to employ the gate 20 it can be removed by taking off the wing nuts 21 and slipping the arms 18 from the studs 17. It is also 75 evident that different lengths of gates may be employed, according to the requirements of the wall constructor. In this view I have shown only the plate 5 provided with a gate, but the same construction, obviously, may 80 be employed for the plate 6, as well, and it is to be understood that the plate 6 is provided with studs 17 which cannot be seen because 85 of the nature of the view.

The plates 5, 6 may be made of any desired 90 length, and the forms will preferably be constructed in several different lengths so as to facilitate the construction of walls having door and window openings and intersecting partitions. For example, a series of 95 form units may be constructed in lengths of from one to five feet so that wall sections of from one foot long to any other desired length, with openings therein and with partitions intersecting, may be constructed by 100 properly combining the different units. The plates shown in Fig. 3 may be assumed 105 to be one foot in length and with such length

one pair of the levers 7, 8 is sufficient. With longer plates a greater number of the levers 7, 8 and their associated parts will be employed. The construction above described, for convenience, may be termed a single unit form.

Now referring to Fig. 4 of the drawings, it will be observed that this view shows two of the single unit forms slightly modified, 10 as regards a few of the elements, and positioned side by side to produce a double unit. But one end gate 20 is shown, and one of the straps 10 of each of the single forms is omitted and in place thereof there is substituted a strap 22 of sufficient length to engage the pivots 9 of both levers 7, said strap 22 being provided at each end with a series of holes 23 for selective positioning of the pivots 9. Also in place of the pivot 11 is 20 substituted a pivot 24 of sufficient length to pass through both levers 8, thus adjustably securing said levers to one another. Thus it is clear that either screw 15 may be separately turned to adjust the plates connected therewith independently of the other plates associated with the other levers 7, 8. The plates 5 may be considered as the outer form plates and the plates 6 as the inner form plates and the inner plates constitute 30 a core.

It is to be understood that it is not absolutely necessary to thus connect the single units together in order that they properly function, but it is advisable to facilitate handling of the forms, placing of the forms in position and removing them from the section of wall after proper setting of the concrete. Also the slight modification in some 35 of the elements, as described, is not essential, since two of the forms shown in Fig. 3, may be employed in combination, without change of the elements, to make a double wall.

It will be observed that in both Figs. 3 and 4 the levers 7, 8 are positioned nearer 45 one end of the plates 5, 6 than the other. In fact the center line midway of the length of the plates 5, 6 cuts exactly through the vertical mid-plane of one of the straps 10 in Fig. 3 and of the strap 22 in Fig. 4. The 50 reason for this construction is that when two single units are associated to form a double unit, as in Fig. 4, the ends of the plates 5, 6 of one single unit are exactly flush with the plates 5, 6 of the other single unit, 55 though the plates of one are reversed with respect to the other.

The double unit shown in Fig. 4 is for the purpose of constructing a hollow or 60 double wall, and it is clear that in the construction of such wall the core of the form comprises the plates 6 of the two single forms, thus making it unnecessary to provide a separate core. In prior hollow wall form constructions, difficulty is experienced 65 in supporting the core in proper position

between the outer form plates, but no such difficulty presents itself in the employment of this double unit form.

It is advisable, when employing the two single unit forms as a double unit form, to attach to one of the plates 6 a cover member or plate 25. This may be done by employing nails 26 or other suitable fastening devices. The plate 25 is secured upon the upper edge of one of the plates 6 and extends over the edge of the other plate 6 so as to cover the space between said plates and prevent the concrete, when being poured into the form, from getting between the plates 6 in the space intended, in the completed wall, to be entirely free of wall material. In the event of it being desired to employ the double unit form adjacent a door or window opening, studding, column, wall tie or an intersecting partition, it is advisable to provide a closure for the end or ends of said forms. For this purpose an end plate 27 is secured by nails or other suitable fastenings 28 to one of the vertical edges of 80 one of the plates 6 and projects over the adjacent edge of the other plate 6.

Now referring to Figs. 1 and 2 of the drawings, there will be seen in said figures a series of double forms and a single form constructed as above described in so far as the use of the levers 7, 8, straps 10, 22, pivots 9, 11, 24, studs 17, wing nuts 21, arms 18, and adjusting screws 15 is concerned. The form side plates are longer than those shown in Figures 3 and 4, and are indicated at 29, 30, 31, 32, 43 and 44. The spaces between the plates 30 are covered by a plate 33 and are closed at their ends by plates 34. The spaces between two of the plates 32 are closed at their tops by a plate 35 and at 90 their ends by plates 36. These various form plates are associated together in such manner as to receive concrete between them for constructing a portion of the hollow outside wall *a* of a structure and also a portion of 100 a partition *b*.

In using the invention, the various forms will be clamped onto the upper marginal portions of the foundation or previously constructed wall section, as clearly shown in Fig. 2, and end gates will be provided wherever the particular construction of the wall requires. Such end gates are indicated at 37 adjacent a door or window frame 38, at 39 to form the outer faces of a corner studding or column and at 40 to space the adjacent ends of one set of core plates 30 from another set of core plates so that the concrete can flow between the ends of said plates and form a wall tie *c*. A gate is also indicated at 41 to space one set of plates 30 from a set of plates 32 and to space one of the plates 29 from one of the plates 31 so that one of the other form plates 43 and an associated plate 44 may be placed endwise 110 120 125 130

relative to the space thus made to permit the concrete to form a wall tie *d* and make the partition *b* continuous with the outside wall.

In making the structure posts will preferably be set at the corners of the structure, one such post being indicated at 42 and the adjacent form plates will abut said post. These posts serve for supporting the line usually employed for marking the position of the wall and to insure perpendicularity of the wall with respect to the earth as the wall increases in height, and also to set the level for openings in the wall.

I claim:

15 In a concrete wall form, the combination of two single forms placed side by side and each comprising a pair of plates, arms pro-

jecting upward from said plates, means between the upper ends of the arms and the plates to pivotally connect one of the arms 20 of each pair of plates to the other arm of the pair, and means to adjustably hold the upper ends of the arms of each pair of plates away from each other, the inner plates of the forms constituting a core for the wall 25 and the arms associated with said inner plates being pivotally connected.

Signed at Los Angeles, California this 1st day of November 1921.

GLEN B. HOAG.
